UNITED STATES PATENT OFFICE.

JOSEPH HAMPSON, JR., OF BALTIMORE, MARYLAND.

DESIGN FOR A MANTEL AND HALL-RACK.

SPECIFICATION forming part of Design No. 25,322, dated March 31, 1896.

Application filed February 6, 1896. Serial No. 578,275. Term of patent 14 years.

To all whom it may concern:

Be it known that I, JOSEPH HAMPSON, Jr., a citizen of the United States, residing at Baltimore, in the State of Maryland, have invented and produced a new and original Design for a Combination Mantel and Hall-Rack, of which the following is a specification.

The accompanying drawing shows a front view of the mantel and hall-rack.

The letter A designates the mantel-shelf, b the vertical supports at each end, and c the breast below the shelf. The open space d below the breast and between the vertical supports b at either side may be occupied as usual by a fireplace or hot-air register. The uprights b' for the rack part are parallel with the vertical mantel-supports b and extend upward past the ends of the mantel-shelf, and at the top is an ornamental cross-piece r, extending from one side to the other. The two side uprights, the top cross-piece, and the

breast below the shelf are provided with hooks e. A panel f, of glass or wood, is above the mantel-shelf and between it and the said top cross-piece.

The essential features of my design consist of a mantel-shelf, vertical uprights below each end thereof and which also extend upward past the end of said shelf, an ornamental cross-piece connecting the top ends of said two uprights, and a panel between the mantel-shelf and said top cross-piece.

I claim—

The design for a mantel and hall-rack as herein shown and described.

In testimony whereof I affix my signature in the presence of two witnesses.

JOSEPH HAMPSON, JR.
